UNITED STATES PATENT OFFICE.

DAVID MILLSPAUGH, OF ANDERSON, INDIANA.

DOOR-GAGE.

SPECIFICATION forming part of Letters Patent No. 748,873, dated January 5, 1904.

Application filed June 13, 1903. Serial No. 161,353. (No model.)

To all whom it may concern:

Be it known that I, DAVID MILLSPAUGH, a citizen of the United States, residing at Anderson, in the county of Madison and State 5 of Indiana, have invented a new and useful Door-Gage, of which the following is a specification.

My invention is an improvement in gages, and while not limited to such use is especially designed for marking doors, indicating the cut to be made for the hinges, the gage being especially adapted for showing the thickness, width, and length of a hinge; and a further object is to combine a square with 15 the gage facilitating the marking of the door and rendering it unnecessary to handle a separate square in addition to the hinge and gage.

My invention consists of the novel features 20 of construction and combination of parts described hereinafter, particularly pointed out in the claims, and shown in the accompanying drawings, in which—

Figure 1 is a perspective view of my gage. 25 Fig. 2 is a plan view of same. Fig. 3 is a side elevation of the gage. Fig. 4 is a section on the line 4 4 of Fig. 3, and Fig. 5 is an end view.

In constructing my gage I employ a smooth 30 bar A, having adjacent one end upwardly and downwardly projecting points A' A², extending from its upper and lower sides, respectively. Sliding loosely on this bar is a clip B, having a downwardly-extending flange B', the rear side of said flange facing the point 35 A², presenting a smooth vertical surface, as shown in Figs. 1 and 3.

The gage proper comprises an open rectangular frame C, having along its rear side 40 a vertical flange C'. Extending rearwardly from intermediate the ends of this flanged side is an integral straight arm C², the said arm terminating in a vertical flange C³ and depending guide-lugs C⁴. The arm C² rests and 45 slides on the upper surface of the bar A and through the clip B, the lugs C⁴ sliding on the sides of the bar and guiding the rear flanged end of the arm.

The front side member of the frame C is 50 extended rearwardly parallel to the arm, as shown at C⁵, and is longitudinally slotted, as

shown at C⁶. The forward end member of the frame C projects beyond and at a right angle to the slotted member and terminates in a point C⁷. A thumb-screw B² works in 55 the upper end of the clip and bears on the arm C², binding it to the bar. A movable pointer slides along the slotted member C⁵, the said pointer consisting of the thumb-piece D, having a shank extending upward 60 through the slot and carrying at its upper end the pointer-head D'. This pointer fits snugly in the slot, so that when moved to any desired position along the member C⁵ it will be held in place until it is again desired to 65 move it.

By loosening the thumb-screw the arm can move along the bar, and the clip can move on both bar and arm. The thickness of the hinge can be gaged between the point A' and the flange C³ and the width of the hinge between the point A² and the flange B' and the thumb-screw tightened, preventing further movement of the clip and arm relative to the bar. By sliding the pointer, the length of the 75 hinge can be gaged by the point C⁷ and pointer-head D'. It will be seen, therefore, that the gage will show at the same time the three dimensions of the hinge. The rectangular frame can be used as a square, and the flange 80 C', which is at right angles to the slotted member and arm, can also be rested against the door or door-frame and will serve as a square.

Having thus fully described my invention, 85 what I claim as new, and desire to secure by Letters Patent, is—

1. A device of the kind described, comprising a bar having points arranged on opposite sides of the bar, a rectangular frame having 90 an arm sliding on said bar, a clip sliding on the bar and arm, a sliding pointer-head carried by the frame, and means for clamping the clip to the arm and bar.

2. A device of the kind described comprising a bar, points projecting above and below the bar adjacent one end, a rectangular frame having a rearwardly-extending arm, said arm sliding on the bar and having guide-lugs engaging the sides of the bar, said frame having 100 also a rearwardly-extending slotted side member, a pointer sliding in said slot, a clip slid-

ing over the arm and bar and means for clamping the arm and clip against movement with reference to the bar.

3. A device of the kind described comprising a bar having upwardly and downwardly projecting points adjacent one end, a rectangular frame, the rear end member of said frame having a vertical flange, and the forward end member terminating in a laterally extending point, and a side member extending rearwardly and being longitudinally slotted, an arm extending rearwardly from

the flanged member of the frame, said arm sliding on the bar and having a vertical flange at its rear end, a clip sliding over said arm and bar and having a depending flange, means for locking the clip and arm in position, and a pointer sliding in the slot of the side member of the frame. 15

DAVID MILLSPAUGH.
